PLASTIC ICE TRAY GRID

Theodore W. Rundell, Abington, Pa., assignor, by
mesne assignments, to Philco Radio and Tele-
vision Corporation, Philadelphia, Pa., a corpo-
ration of Delaware

Application December 24, 1943, Serial No. 515,558

7 Claims. (Cl. 62—108.5)

The present invention relates to ice molds, and more particularly to a grid of the class commonly used in the ice trays of household refrigerators for molding ice cubes or other small bodies of a size and shape suitable for domestic uses.

It has been proposed to provide combination grid-and-cover members for ice trays, but the prior devices have been unsatisfactory by reason of certain inherent faults which give rise to difficulties, either in filling the tray with water for production of the ice bodies or in freeing the member from the frozen bodies to make the latter available for use.

One of the objects of the present invention is to provide a combined grid and cover which, when in place within the tray, will not prevent nor unduly complicate the filling of the tray with water; and which may be readily removed from the tray at any time either before or after the formation of the ice has been completed.

More specifically, an object of the invention is to provide a grid-and-cover member of a character to establish within the tray a plurality of enclosed freezing chambers or compartments, said member being constructed so as to facilitate the filling of the chambers with water, and so as to afford an automatic separation of the member from the fully formed ice bodies whereby the member may be withdrawn readily from the tray and from the ice bodies, the latter remaining in the tray in condition for immediate use.

Another object of the invention is to provide a grid-and-cover member of the self-releasing character described above wherein the automatic release is effected by action of expansion forces resulting from the freezing of the water within the enclosed chambers aforesaid.

The invention further contemplates a grid-and-cover member of the character set forth having means for producing a supply of ice in addition to the bodies produced within the said freezing chambers and relied upon to afford the automatic release.

Other novel features of the invention will appear from the following detailed description and from the accompanying drawing, in which:

Fig. 1 is a top plan view showing the improved combination cover and grid in position within an ice tray;

Fig. 2 is a fragmentary perspective view of the assembly shown in Fig. 1 with portions of the assembly broken away to illustrate the cooperative relation between the cover-and-grid structure and the tray;

Fig. 3 is a side elevational view illustrating the grid-and-cover elevated in the tray as in the act of insertion or removal; and

Fig. 4 is a fragmentary sectional view on the line 4—4, Fig. 1.

With reference to the drawing, the reference

numeral 1 designates an ice tray substantially of conventional form and preferably composed of metal having relatively high heat conductive capacity and stamped or otherwise shaped from 5 a single sheet of said metal to the elongated substantially rectangular form shown. The side walls 2 and end walls 3 are preferably inclined so as to converge toward the bottom wall 4; and the said side and end walls are formed at their tops with an outward lateral flange 5 which extends continuously around the top of the tray and which terminates at its outer edge in an upstanding bead 6.

The grid-and-cover member forming the subject of the invention is designated generally by 15 the reference numeral 7. Preferably the member is molded in one piece from suitable material having a lower heat conductive capacity than the material of the tray 1, and many plastics, such 20 for example, as that known in the trade as "Vinylite," are well adapted for this purpose.

As shown in the drawing, the combination 25 grid-and-cover member 7 is of a size and shape to fit within the confines of the upstanding bead 6 of the tray 1, and has a marginal edge portion 8 which, when the member is inserted in the tray, will engage the flange 5 of the latter as best shown in Figs. 2 and 3. A handle 9 may be provided at one end of the member to facilitate insertion and removal thereof in and from the tray.

Arranged at intervals along the length of the member and within the confines of the marginal edge portion 8, are a number of trough-like V-shaped recesses 10, these recesses in effect 35 alternating with cover portions 11. The walls 12 and 13 of the recesses 10 extend to and contact with the bottom wall 4 of the tray when the grid-and-cover member is in normal position within the latter, as shown in Figs. 2 and 4. Rib sections 14 are joined to the under sides of the cover 40 portions 11 and to the slanting sides of said recesses 10, and serve to divide the spaces defined by said cover portions and sides into two compartments. In the present instance the ribs 14, 45 which extend to the lower edges of the walls 12, as shown in Figs. 2 and 3, lie on the longitudinal center line of the grid-and-cover member and the compartments are therefore approximately of the same size. Similar ribs 15 extend from the outer walls of the end recesses 10, as shown in 50 Fig. 3.

The ribs 14 and 15 and the depending walls of the recesses 10 coact with the bottom, side and end walls of the tray to form within the latter a 55 plurality of separate ice compartments enclosed at the top by the cover portions 11. To this end, and as previously set forth, the lower edges of the downwardly converging walls of the recesses 10 and of the said ribs 14 and 15 will normally engage the bottom wall 4 of the tray. Similar-

ly, the outer edges of the ribs 15 and the end walls 13 of the recesses 10 will contact the end and side walls of the tray, respectively, and are contoured accordingly, as shown in Figs. 3 and 4. The interior of the tray is thereby divided into a plurality of compartments 16 each of which is covered for the greater part by one or other of the cover portions 11 and within which the water content of the tray may be frozen into individual ice bodies. The recesses 10 may also be utilized as freezing compartments, thereby increasing the ice-production capacity of the tray.

In the freezing process, the water within the aforesaid compartments freezes first along the walls of the tray 1 and continues to freeze in a direction away from said walls, this by reason of the relative difference in heat conductive capacity of the tray and combination grid-and-cover member 7. Accordingly, the expansion forces arising from the ultimate freezing of the water are directed substantially toward said grid-and-cover member with the result that the said forces act to displace said member in relation to the tray and to the ice bodies formed within the latter. Such displacement breaks the bond between the said ice bodies and the surfaces of said member, leaving the latter free for lifting from the tray and from the ice cubes which remain exposed and accessible within the tray. The action above referred to is known in the art and forms no part of the present invention.

The marginal edge 8 of the member 7 is of extra width opposite the ends of the portions 11, so that in these areas the said edge in part overlies the compartments 16 and in effect forms portions of the covers of the latter. In accordance with the invention, the said marginal edge is provided with openings 17 which afford access to the compartments and through which water may be supplied to the latter while the member 7 is in position in the tray. Also, for a purpose hereinafter explained, the cover portions 11 are formed with upper surfaces of rectangular pyramidal form presenting inclined planes 18 and 19 terminating, respectively, at their lower ends in the recesses 10 and in the marginal edge 8 opposite the openings 17.

In use, the combination grid-and-cover member 7 may be placed in the tray 1 by placing one end of the member on the flange 5 and against the bead 6 of the tray, and thereafter through the medium of the handle 9 lowering the other end into place as indicated by the arrow in Fig. 3. Water may then be poured or be allowed to run over the member 7 thereby filling the V-shaped recesses 10 and, by way of the openings 17, the compartments 16, the water being directed by the inclined surfaces 18 and 19 to the said recesses and openings, and also to the marginal edge 8 from which it flows into said recesses and openings. In this connection, it is to be noted that the bead 6 projects above the plane of the marginal edge 8 and, therefore, acts as a means for directing the flow of water to the recesses 10 and to the openings 17.

The water-filled tray is then placed in the freezing compartment, conventionally provided in automatic refrigerators, wherein the water is converted into ice. After freezing, the combination grid-and-cover member may readily be removed from the tray, and from the ice bodies within the compartments 16, which bodies will remain within the tray. The ice within the trough-like recesses 10 may be liberated by imparting a slight twisting motion to the grid-and-cover member.

It is to be noted that should it be desired to construct the combination ice tray grid-and-cover member without provision for producing a supply of ice other than that produced in the primary compartments 16, then the V-shaped portions embracing the recesses 10 may be formed as solid or sealed parts of the structure from which water is excluded. It will be understood also that other modifications in the specific structure herein shown and described may be made without departing from the invention.

I claim:

1. Ice molding means of the character described, comprising an ice tray having a marginal flange, a combination grid-and-cover member cooperative with the tray to form within the latter confined areas constituting individual freezing compartments, a marginal edge portion of said member being arranged for engagement with the flange of said tray and having therein means affording access to said areas for introduction of a liquid medium.

2. A combination ice-tray grid and cover comprising cover portions, generally V-shaped portions depending from said cover portions, and a marginal edge projecting laterally from said cover portions and having openings extending therethrough.

3. A combination ice-tray grid and cover comprising cover portions, generally V-shaped portions depending from said cover portions, and a marginal edge projecting laterally from said cover portions and having openings extending therethrough, said cover portions having inclined surfaces directed toward the openings in said marginal edge.

4. A combination ice-tray grid and cover comprising an alternating arrangement of cover portions and open-topped generally V-shaped trough-like portions, said cover portions having openings extending therethrough and inclined surfaces directed toward the openings in said cover portions and toward the open tops of said V-shaped trough-like portions.

5. A combination ice-tray grid and cover comprising alternating cover portions and depending generally V-shaped portions, rib sections depending from said cover portions and interconnecting said V-shaped portions intermediate the length of the latter, said rib sections extending substantially to the bottoms of the V-shaped portions, and said cover portions having openings extending therethrough.

6. A combination ice-tray grid and cover comprising alternating cover portions and depending generally V-shaped portions, rib sections interconnecting the V-shaped portions and extending from said cover portions substantially to the bottoms of said V-shaped portions, said cover portions having openings extending therethrough and inclined surfaces directed toward said openings.

7. A combination ice-tray grid and cover comprising spaced cover portions and intervening generally V-shaped open-top trough-like portions, rib sections depending from the cover portions and attached to said V-shaped portions and corresponding in height substantially to the latter, said cover portions having openings extending therethrough and inclined surfaces directed toward the openings in said cover portions and toward the open tops of said V-shaped trough-like portions.

THEODORE W. RUNDELL.
